UNITED STATES PATENT OFFICE.

THOMAS WEST, OF PLYMOUTH, PENNSYLVANIA.

DESIGN FOR A STOCKING OR SIMILAR ARTICLE.

SPECIFICATION forming part of Design No. 34,770, dated July 9, 1901.

Application filed May 6, 1901. Serial No. 59,063. Term of patent 3½ years.

To all whom it may concern:

Be it known that I, THOMAS WEST, a citizen of the United States, residing at Plymouth, in the county of Luzerne and State of Pennsylvania, have invented and produced a new and original Design for Stockings or Similar Articles, of which the following is a specification, reference being had to the accompanying drawing, forming part thereof.

10 In the drawing I have shown a side view of a stocking, illustrating my new design. The reverse side is not shown, as the design is similar upon both sides.

15 The leading or material feature of my design consists of the representation of a number of buffaloes displayed upon the article, and, as herein shown, the buffaloes and the

ground of the article contrast in color or shade.

The design is applicable to all sorts of hosiery, whether stockings, socks, or similar articles.

Having thus described my invention, what I claim as new, and desire to secure by Letters Patent, is—

20 The design for a stocking or similar article, substantially as herein shown and described.

25 In testimony whereof I have signed my name to this specification in the presence of two witnesses.

THOS. WEST.

Witnesses:

SAMUEL SALSBURG,
F. H. ARMSTRONG.
